Specification of Letters Patent. Patented Mar. 22, 1921.

Application filed August 12, 1918. Serial No. 249,557.

To all whom it may concern:

Be it known that I, WILLIAM P. MICHAELSEN, a citizen of the United States, and a resident of Minneapolis, in the county of 5 Hennepin and State of Minnesota, now a member of Company C, 326th Field Signal Battalion, stationed at Camp Wadsworth, Spartanburg, South Carolina, have invented certain new and useful Improvements in 10 Briquetting-Presses, of which the following is a specification.

My invention relates to presses for forming loose, granular, fibrous or pulverulent materials into briquets, particularly materials such as peat, lignite, coal-dust, saw-dust, and similar substances suitable for fuel. It is the object of my invention to provide a plurality of molds rotatably mounted and arranged to pass successively positions at 20 which the loose material is fed thereinto, then to positions at which the charge of material is compressed into a briquet, then to positions at which the briquet is ejected from the mold, and finally returning to the feed position, whereby the formation of the briquets may be continued indefinitely and automatically, without attention other than to continue the supply of material to the machine. A further object of my invention 25 is to provide efficient and durable actuating means for the pressing mechanism. A further object of my invention is to provide means for varying the stroke of the main compression plunger, while maintaining the stroke of the feed-plunger constant or substantially so. A further object of my invention 30 is to provide a novel actuating device for causing intermittent movement of the rotary mold-cylinder. More particular objects of my invention will appear herein- 35 after.

In the accompanying drawings Figure 1 is a side view of a machine embodying my invention, Fig. 2 is a longitudinal vertical 45 section on the line 2—2 of Fig. 3, Fig. 3 is a plan view of the machine, with a portion in horizontal section through the axis of the mold-cylinder, and Figs. 4, 5 and 6 are detail transverse vertical sectional views on the 50 lines 4—4, 5—5 and 6—6, respectively, of Fig. 1.

In the illustrated embodiment of my invention I provide a main frame comprising a pair of side-pieces 7 and front and rear 55 end-plates 8 and 9, the general form of said

frame being rectangular, the inner sides of the frame-members being plane-surfaced and substantially vertical, and the outer sides of said members being variously ribbed and flanged, as shown. The rear upper portions of the side-pieces 7 are recessed to receive journal-blocks 10, in the upper portions of which are formed bearings for a transverse shaft 11, said shaft carrying at one end a fly-wheel 12, and at the other end having a pulley 13 which may be connected by belt with a suitable source of power. A pinion 14 is secured on the intermediate portion of the drive-shaft 11, said pinion meshing with a gear 15 which is secured to a 60 shaft 16, said shaft extending parallel with the shaft 11 and being journaled in bearings formed in the side-pieces 7 and the lower portions of the blocks 10.

Eccentrics 17 are mounted on the shaft 75 16 adjoining the inner sides of the frame-members 7, said eccentrics each having connected therewith an eccentric-rod 18 which extends forwardly therefrom and is actuated reciprocatingly by the eccentric. The front 80 ends of the eccentric-rods 18 are forked or longitudinally slotted and fit slidably upon rectangular guide-blocks 19 carried on a transverse shaft 20. The end-portions of said shaft 20 are mounted in blocks 21 which 85 are disposed in vertical slots in the frame side-pieces 7, there being a plurality of shims 22 disposed above and below said blocks 21, and screws 23 being arranged at the lower ends of the slots for retaining the 90 members therein by pressing the same toward the upper ends thereof. By transposing the plates 22 from above to below, or from below to above the bearing-blocks 21, the position of the latter may be varied verti- 95

cally, for a purpose which will appear hereinafter. A transverse shaft 24 has the ends thereof held in bearings in the intermediate portions of the eccentric-rods 18, and the central portion of said shaft extends through 100 a block 25 which is disposed slidably in a slot formed in the central portion of a rocking-lever 26. Said lever is fulcrumed at its lower end on the intermediate portion of a shaft 27 which extends through suitable bearings therefor in the lower portions of the frame-members 7. A shaft 28 extends through the upper portion of the rocking-lever, and short connecting rods 29 are pivoted on the end-portions of said shaft. The 110

front ends of said connecting-rods are pivotally connected with the end-portions of a shaft which extends through the rear portion of a crosshead 30, said crosshead being slideable in horizontal guideways therefor formed in the upper portions of the frame-members 7, as shown. The stroke or extent of movement of the crosshead, imparted thereto by the described actuating connections, may be varied by adjusting vertically the blocks 21 which support the ends of the shaft 20. It will be seen that when said shaft 20 is lowered the shaft 24 passes through a portion of the slot in the rocking-lever 26 nearer to the fulcrum-shaft 27, so that with the same stroke of the eccentric-rods 18 the rocking-lever will be moved through a greater angle, and thereby increase the stroke of the cross-head. Conversely, raising of the shaft 20 causes the shaft 24 to work in a portion of the rocking-lever more distant from the fulcrum-shaft, so that the angular movement of the rocking-lever and the stroke of the cross-head are reduced.

Eccentrics 31 are secured on the shaft 16 adjoining the outer ends of the bearings for said shaft in the side-pieces 7 of the frame. Said eccentrics actuate reciprocatingly eccentric-rods 32 which extend forwardly and downwardly therefrom, the ends thereof being forked and straddling the intermediate portions of rocking-levers 33 of which the lower ends are fulcrumed on end-portions of the shaft 27 which extend outside the frame-members 7. The forked ends of the eccentric-rods 32 are pivotally connected with the rocking-levers 33 through the medium of cross-pins 34 carried by blocks arranged in slots in the rocking-levers, shim-plates 35 being arranged above and below said blocks, and the several members being held in place by cotters 36, as shown. Transposition of the shim-plates from the lower to the upper portions of the slots, or vice versa, enables the cross-pins to be moved toward or away from the fulcrum-shaft and increases or reduces the angular stroke of the rocking-levers. Connecting-rods 37 are pivotally connected with the upper ends of the rocking-levers 33 and extend forwardly therefrom to connect pivotally with the intermediate portions of pawl-levers 38 which are fulcrumed on pins 39 extending out from the lower portions of the frame-members 7 beneath the bearings of the mold-cylinder shaft. The upper ends or heads of the levers 38 are bored to receive slidably the pawl-pins 40, springs 41 being provided, as shown in Fig. 4, for pressing the pawl-pins in toward the ratchet-plates 42 with which they coöperate. The ratchet-plates 42 are secured on the end-portions of a large tubular shaft 43 which is revolubly mounted in bearings formed in the upper forward portions of the frame-

members 7. Each of the ratchet-plates has therein a plurality of uniformly-spaced radially extending slots 44 into which the pawl-pins 40 drop at the rearward limits of movement of the levers 38, and the stroke of said levers is so adjusted that during each forward movement thereof the ratchet-plates and shaft 43 are thereby rotated through the angles included between adjacent pairs of the slots 44. In the faces of the ratchet-plates, between each pair of the slots 44, there are grooves or channels 45 which are curved so as to be concentric with the fulcrum-pins 39 of the pawl-levers when the respective grooves are at the lowermost portion of the ratchet-plates. The bottoms, or inner sides of the grooves 45 are inclined axially of the shaft 43, so that during the rearward strokes of the pawl-levers 38 the pins 40, by engaging said inclined surfaces, are pressed outwardly until, at the rear end of the stroke, said pins are actuated by the springs 41 to pass into the succeeding slots 44.

The mold-cylinder is secured upon the intermediate portion of the tubular shaft 43, and comprises a pair of end-plates 46 arranged on the shaft adjoining the inner ends of the bearings therefor, and a central member 47 to which said end-plates are secured. Said member 47 has formed therein a series of recesses or mold-cavities 48 which open at the peripheral portion of the member, and of which the ends are closed by the plates 46. The mold-cavities 48 are equally spaced circumferentially of the cylinder, and are the same in number as the slots 44 of the ratchet-plates. The inner portions of the mold-cavities are tapering or wedge-shaped, being smaller at the bottoms than at the outer sides. Each of the mold-cavities is provided at the bottom with an ejector-plate 49 from which two or more stems 50 extend in radially through the side of the shaft 43, and within the bore of the shaft each of said stems has a coil spring 51 disposed around the same and bearing against a collar thereon to press the same inwardly and thereby normally retain the ejector-plate in the bottom of the mold-cavity. A rod 52 extends through the bore of the shaft 43 coaxially therewith, the ends of said rod being polygonal and fitting into similarly shaped openings in brackets 43, by which the rod is held fixedly. On said rod 52, adjoining the inner ends of the stems 50, cam-disks 54 are secured so as to be engageable by said stems during rotation of the mold-cylinder. On the lower portions of the cam-disks are projecting parts 55 which engage and push outwardly the passing stems, so that the ejector-plates are thereby displaced from the inner ends of the mold-cavities, as shown in Fig. 2.

A feed hopper or chute 56 is arranged at 130

the front side of the mold-cylinder, the sides of said chute being fitted around the peripheral edges of the end-plates 46 of the cylinder, and the chute being supported by 5 curved brackets 57 resting on the upper edges of the frame-members 7, as shown in Fig. 5. In the lower portion of said chute 56 there is formed a horizontal guideway for a reciprocating feed-block or plunger 58, from the ends of which pins 59 extend through slots in the sides of the chute beneath the brackets 57. Said pins 59 fit pivotally in blocks 60 which are slidably disposed in the upper forked ends of levers 15 61, and said levers are fulcrumed on pivot-bolts 62 which extend through the frame-members 7 adjoining the front ends thereof, as shown. The levers 61 are actuated reciprocatingly by means of the eccentric-20 rods 18, the latter having near the front ends thereof downwardly extending lugs 63 from which connecting-rods 64 extend forward horizontally to the lower ends of said feed-levers 61. It will be noted from 25 Figs. 4 and 5, that while the connecting-rods 64 are disposed between the sides of the frame, said rods are so arranged laterally as not to be under the mold-cavities, so that said rods do not interfere with ejection 30 of the compressed material from the mold-cavities at the lower portion of the cylinder.

The main compression-plunger 65 is carried by the cross-head 30, being secured thereto as shown in Fig. 3, and being proportioned so as to pass into the outer portions 35 of the several mold-cavities as the same are successively presented thereto by the intermittent rotary movement of the mold-cylinder. The pawl and ratchet-plate actuating devices for the mold-cylinder are so timed, and the movements thereof so proportioned, that each actuating stroke of the pawls will bring one of the mold-cavities 40 into register with the plunger 65, while at the opposite or front side of the cylinder one of the mold-cavities will be in register with the reciprocating feed-block. The actuating devices for the crosshead and feed-block are so timed that said parts are withdrawn 45 from the cylinder during the periods of movement of the cylinder, and so that the cylinder remains stationary as the reciprocating parts approach or enter the mold-cavities. It will be seen that raising or 50 lowering of the shaft 20, to vary the stroke of the crosshead 30 as before described, will not appreciably vary the movement of the feed-block 58, so that varying degrees of 55 compression of the material may be attained by adjusting the stroke of the crosshead, without altering the feed mechanism. For convenience of assembling and dis-assembling the mechanism, the frame-members 7 60

have openings therein, as shown in Fig. 1, 65 opposite the ends of the connecting-rods 64 and of the shaft 24.

The operation of the mechanism as a whole will be apparent from the foregoing description of its construction and of the 70 operation in detail of the several groups of mechanism. The material to be formed into briquets is fed continuously into the chute 56 from any suitable source, and power is applied to the pulley 13. By the described 75 actuating mechanism the mold-cylinder is rotated intermittently to bring the mold-cavities successively into register with the plunger 65 and opposite the feed-block 58, the direction of movement of the cylinder 80 being as indicated by arrows in Figs. 1 and 2. The plunger and feed-block are moved simultaneously toward the cylinder while the same is at rest, the feed-block pushing material from the feed-chute into the respectively adjacent mold-cavity and lightly compressing the same therein. Succeeding movements of the mechanism carry the filled mold cavities into register with the plunger 85 65, where the material is compressed into 90 the cavities, so as to be formed into a briquet conforming in shape to the mold. Then, by means of the ejector-plates 49, the briquets are loosened and partially ejected from the 95 cavities, so as to fall therefrom at the lower side of the cylinder, the briquets passing down between the connecting-rods 64 and being received in a chute or conveyer disposed beneath the front portion of the machine. 100

It will be obvious that by suitable formation of the mold-cavities, and of the forward face of the compression-plunger 65, the briquets may be made of any desired form such as to be capable of satisfactory ejection 105 from the mold; and it will also be apparent that the mold-cavities may be in longitudinally arranged series so that a plurality of the briquets may be formed at each stroke of the plunger. 110

Now, having described my invention, what I claim and desire to secure by Letters Patent is:

1. In a press of the class described, an axially-horizontal mold-cylinder having a plurality of peripheral mold-cavities therein, reciprocating means at one side of said cylinder for feeding material into the mold-cavities, reciprocating means at the opposite side of the cylinder adapted to enter the mold-cavities to compress material therein, means for actuating said feeding means and compressing means in unison, means for varying the stroke of the compressing means, means for intermittently rotating the mold-cylinder to dispose the successive mold-cavities in register with the feeding means and compressing means, and means for 115 120 125

ejecting material from the mold-cavities at positions intermediate the compressing and feeding positions.

2. In a press of the class described, a cylinder having a plurality of peripheral mold-cavities therein, a crosshead movable toward and away from said cylinder and having a part adapted to enter a mold-cavity in the cylinder, means for intermittently 10 moving the cylinder to present the successive mold-cavities in register with said part, a rocking-lever connected with said crosshead and having a longitudinal slot therein, a reciprocating actuating member having a fixed travel and movable in said slot, and means for moving said member toward and 15 away from the lever-fulcrum transversely of its path of reciprocation to vary the stroke of the rocking-lever and crosshead.
3. In a press of the class described, the combination with a horizontal cylinder having a plurality of peripheral mold-cavities therein, of a compression-plunger and a feed-block movable reciprocatingly at opposite sides of the cylinder, means for intermittently actuating the cylinder to present the mold-cavities successively to said 20
- 25

feed-block and plunger, rocking-levers connected with said block and plunger, and reciprocating actuating means for said 30 rocking-levers adapted to move the block and plunger in opposite directions.

4. In a press of the class described, a movable mold-member having a plurality of mold-cavities therein, a plunger adapted 35 to enter said mold-cavities to compress material therein, means for intermittently moving the mold-member to present its cavities successively in register with said plunger, a crosshead carrying said plunger, a slotted rocking-lever connected with said crosshead, an eccentric-driven rod movable transversely of said rocking-lever, a member carried by said rod and movable in the slotted portion of the rocking-lever to 40 actuate the same, guiding means for one end of said rod, and means for varying the position of said guiding means to change the relation of the rod to the rocking-lever longitudinally thereof and thereby move the 45 member carried by said rod toward or away from the fulcrum of the rocking-lever to vary the stroke thereof.

WILLIAM P. MICHAELSEN.
